WAFFLE IRON AND TEMPERATURE CONTROL AND INDICATOR THEREFOR

Allan M. Young, Meriden, Conn., assignor to
Manning, Bowman & Co., Meriden, Conn., a
corporation of Delaware

Application March 4, 1938, Serial No. 193,866

7 Claims. (Cl. 219—19)

This invention relates to electric waffle irons and the like.

One object of the invention is an electric waffle iron embodying a novel and improved means for regulating the temperature thereof.

5 A further object of the invention is an electric waffle iron embodying a novel and improved temperature control and indicator in combination.

A further object of the invention is an electric waffle iron embodying a novel and improved temperature regulating and adjustable mechanism including a centrally disposed knob on the upper part.

15 A further object of the invention is an electric waffle iron of the above indicated character characterized by its simplicity in the control and regulation of the temperature, by its inexpensive construction and by the efficiency and reliability of its regulating mechanism.

20 Further objects of the invention will herein-after appear.

For a better understanding of the invention reference may be had to the accompanying drawings forming a part of this application wherein—

25 Fig. 1 is a sectional view through a waffle iron embodying the invention;

Fig. 2 is a plan view of the upper grid and associated parts;

Fig. 3 is a detail view of a part of the automatic temperature regulating mechanism;

30 Figs. 4a, 4b and 4c are views of parts indicating the method of assembly; and

Fig. 5 is a top plan view of a part of the iron.

Referring to the drawings, the invention is illustrated as embodied in a waffle iron 1 having a 35 base support 2. The lower half of the waffle iron is indicated diagrammatically at 3 and the upper half is indicated at 4, it being understood that the part 4 is hinged to the part 3 in the usual manner so that the part 4 may be lifted and lowered about the hinge in the usual manner of waffle irons. The hinge and the handle for lifting and lowering the upper part 4 of the waffle iron are omitted from the drawings for convenience and illustration.

45 The upper part 4 of the waffle iron comprises a conventional cover 5, a porcelain unit ring 6 and a grid plate 7. The cover 5 and grid plate 7 are fastened together as a unit in any suitable manner. The ring 6 carries a conventional electric heating coil 8.

An insulating block 10 is mounted upon and fastened to the upper side of the grid plate 7 in any suitable manner, as for example by means of the screw 10'. This block carries an interrupter

for the heating circuit, which interrupter comprises a fixed contact 11 carried by a metallic angle piece 12, this metallic angle piece 12 being fastened to the block 10 in any suitable manner and having a terminal 13 to which is attached a wire 14 leading to the heating coil. A movable contact 16 is carried by a spring arm 17, this arm 17 being also suitably mounted upon and fastened to the block 10 and having a terminal 18 to which is connected a wire 15 leading to the other side of the gap in the circuit of heating coil 8. The spring arm 17 is biased to close the circuit at the contacts 11 and 16 and carries on its outer end an adjustable screw 19 with which a thermostatic element 20 engages for interrupting the circuit when the temperature reaches the predetermined value to which it is adjusted. This thermostatic element 20 may be of any conventional character, as for example bi-metallic, and it carries a metallic button 21 on the upper side thereof for engaging the adjustable screw 19 of the spring arm 17. This button 21 is insulatedly carried by the element 20 in any suitable manner, as for example being in the form of a rivet passing through an opening in the element 20 and insulated therefrom by insulation washers 22.

20 The thermostatic element 20 is biased by a spring 23 upwardly in a direction to engage the adjustable screw 19 and interrupt the circuit at the contacts 11 and 16, this spring 23 engaging at its free end the grid plate. The element 20 and the spring 23 are fastened together by rivets 24 which rivets in turn secure these elements to a plate 25, the latter having ears 26 turned upwardly from its sides which are journaled on a pin 26' carried by the legs of a U-shaped bracket 27, the bracket 27 being fastened to the upper side of the grid plate 7 in any suitable manner, as for example by means of the screws 28.

25 The porcelain ring 6 is firmly fastened to the upper side of the grid plate 7 by means of a triple threaded screw 30 and a hold down strap or metallic bar 31. The latter bridges the circular opening formed by the ring 6, on a diameter thereof, and is provided with an opening through which passes the screw 30, the latter having a screw threaded part at its lower end which is screwed home into the centrally disposed boss 7' projecting upwardly from the center of the grid plate 7. A spacing sleeve 32 is disposed between the boss 7' and the strap 31 and the screw 30 has a screw threaded part intermediate its ends with which engages a nut 33, the latter being screwed down tightly against the strap 31 to cause the ends thereof to bind and grip the ring 6 and 35

thereby firmly hold the ring 6 and the grid plate 7 as a unit.

The triple threaded screw 38 is provided with screw threads at its upper end for the reception of an adjustable threaded sleeve or bushing 35, and by the rotation of this sleeve or bushing 35 the thermostatic element 28 may be adjusted with respect to the adjustable screw 19 to vary the temperature which is to be automatically maintained. The up and down movement of the bushing 35 is communicated to the element 28 by means of a metallic strip 36 having an opening adjacent one end to freely receive the screw 38. At its other end this member 36 has its end turned downwardly at right angles to the main body thereof, and this end which is thus turned downwardly is slotted for a portion of its length to form feet 38 which project downwardly through notches 31' cut in the sides of the strap 31. These feet 38 are then bent outwardly to a position as indicated, whereby this member 36 is anchored to the strap 31 for pivotal movement with respect to the strap 31. The opposite end of this member 36 can thus pivot towards and away from the strap 31 and is provided with a tongue 36' which passes through an opening in the strap 31 and engages the upper side of the thermostatic element 28. As above indicated, the thermostatic element 28 is biased in an upward direction and by rotating the bushing 35 which engages the upper side of the member 36 the distance of the thermostatic element 28 from the adjustable screw 19 may be varied.

The cover 5 is provided with a centrally disposed opening 40 for the reception of a temperature indicating and swiveling and holding member 41 for an annular adjusting knob 42. The member 41 is provided with a downwardly depending skirt 41' which extends through the opening 40 and is provided with tongues 43 which are peaned over into the notches 40' formed in the periphery of the opening 40, the member 41 thus being anchored against rotation on the cover 5 and against removal therefrom. The member 41 is provided at its upper periphery with a circular shoulder or flange 44 projecting outwardly beyond the skirt, and in the assembled position this shoulder 44 engages a co-operating shoulder 45 formed on the interior of the annular knob 42. This knob 42 is provided with a flat under surface 42' and rests upon the correspondingly flat top part of the cover 5. The annular knob 42 may thus swivel about the skirt 41' of the member 41 for the purpose of adjusting the thermostatic element. For this purpose the knob 42, which is preferably formed of Bakelite or some other suitable insulating material, is operatively connected with the adjusting bushing 35. This operating connection comprises a flat arm 47, which is rigidly fastened to the bushing 35 in any suitable manner, and this arm is provided with an upstanding tongue 48 which passes through an arcuate slot 49 formed in the cover 5 and into a recess 50 formed on the under side of the annular knob 42. Thus the annular knob 42 is rotatable through an angle limited by movement of the thermostatic element 28 or by the arcuate slot 49. The indicating unit 41 comprises an indicating needle 51 journaled therein and operable by a thermostatic element 52 in the conventional manner. A transparent cover 53 is carried by the unit 41 in any suitable manner.

The operation is clear from the above description. By merely rotating the annular knob 42, the thermostatic element 28 may be adjusted to

maintain any temperature that it may be desired to maintain, and the waffles may be safely left in the iron for some time beyond the cooking time without burning. The whole indicating and regulating mechanism is thus concentrated and located in the center of the cover and the indicating device is located within the adjusting knob. The assembly is a simple one and inexpensive to manufacture and assemble.

I claim:

1. In an electric waffle iron and the like, a grid plate, a heating unit ring, a holding member disposed on a diameter of the ring, a screw passing through an opening in the said member and screw threadedly fastened to said grid, a nut screw threadedly attached to said screw and engaging said member to fasten the heating unit ring and the grid plate firmly together, a cover for said grid and heating unit ring, a temperature indicating unit mounted centrally on said cover, an annular knob journaled on said cover and about said temperature indicating unit for rotary movement thereon, a thermostatic regulating means and operative connections between said means and the annular knob comprising a threaded bushing on said screw and a finger attached to said bushing and in engagement with the annular knob for adjusting said thermostat element.

2. In an electric waffle iron, a cover therefor, a temperature indicating unit mounted upon said cover, an annular adjustable knob journaled for rotary movement about said unit, a thermostatic element for automatically regulating the temperature and operative connections between said annular knob and said thermostatic mechanism for setting the thermostatic element for different temperatures.

3. In an electric waffle iron a cover therefor, a temperature indicating unit comprising a downwardly extending cylindrical skirt and a circular flange at the upper part thereof, said unit being mounted on the cover, an annular knob journaled about said skirt and between said flange and the cover for rotary movement, a thermostatic mechanism for automatically regulating the temperature and an operative connection between said annular knob and said mechanism whereby the thermostatic mechanism may be adjusted to maintain the desired temperature by rotating the annular knob.

4. In an electric waffle iron a thermostatic mechanism for regulating the temperature thereof, a cover over said mechanism, a bearing unit mounted on said cover, an annular knob journaled on said unit for rotary movements thereabout and an operative connection between said thermostatic mechanism and said annular knob whereby the thermostatic element may be set to operate at different temperatures, the operative connection including a screw and a screw threaded bushing thereon, said bushing having an arm fastened thereto with a finger projecting up through an opening in the cover and into a recess formed in the annular knob.

5. In an electric waffle iron a thermostatic mechanism for regulating the temperature thereof, a cover over said mechanism, a bearing unit mounted on said cover, an annular knob journaled on said unit for rotary movements thereabout and an operative connection between said thermostatic mechanism and said annular knob whereby the thermostatic element may be set to operate at different temperatures, the operative

- connection including a screw and a screw threaded bushing thereon, said bushing having an arm fastened thereto with a finger projecting up through an opening in the cover and into a recess formed in the annular knob, and a pivoted member disposed between the bushing and said thermostatic mechanism.
6. In an electric waffle iron, a grid plate, a heating unit ring disposed on said grid, an elongated strap disposed on a diameter of said ring, a bolt screw threadedly engaging said grid plate and clamping said strap in engagement with the ring to hold it firmly against the grid, a thermostatic element biased in one direction, a pivoted member carried by said strap and engaging the

thermostatic element for adjusting the same, a cover, a knob journaled on said cover, and operative connections between said knob and the pivoted member for adjusting the thermostatic element.

7. In an electric waffle iron, a grid plate, a heating unit, a temperature regulator, and means for fastening the heating unit to the grid plate and for adjusting the regulator comprising a triple threaded screw element screw-threadedly 10 engaging said grid plate at one end, screw-threadedly engaging a fastening means intermediate its ends and screw-threadedly engaging an adjusting means at its other end.
